[57] CLAIM

The ornamental design for the covered salad bowl or the like, as shown.

DESCRIPTION

FIG. 1 is a top perspective view of the covered salad bowl or the like showing my new design;
FIG. 2 is a side elevational view thereof;
FIG. 3 is an end elevational view thereof;
FIG. 4 is a top plan view thereof;
FIG. 5 is a bottom plan view thereof; and
FIG. 6 is a cross-sectional view on an enlarged scale taken along line 6—6 of FIG. 4.
